UNITED STATES PATENT OFFICE.

JEROME M. CARLEY, OF EAST GREENBUSH, NEW YORK.

METHOD OF CONTROLLING AN ELECTRIC CIRCUIT AND DESIGNATING SAME.

1,281,288.

Specification of Letters Patent. Patented Oct. 15, 1918.

Application filed March 7, 1918. Serial No. 220,931.

To all whom it may concern:

Be it known that I, JEROME M. CARLEY, a citizen of the United States, and resident of East Greenbush, in the county of Rensselaer 5 and State of New York, have invented a certain new and useful Method of Controlling an Electric Circuit and Designating Same, of which the following is a specification.

10 This invention relates to a method of controlling an electric circuit and has for its object a means for opening and closing a circuit in a simple and convenient manner; also a means for designating said circuit.

15 In electrical construction work, it is common practice to terminate the conductors at intervals, as for instance, at junction boxes used where cables or wires connect to other cables or wires. For this purpose a 20 terminal is used having two independent binding posts supported from an insulating base, to each of these posts a conductor is connected, and between the posts a strip of sheet metal connects the terminals.

25 A construction of this kind is illustrated in Figures 1 and 2 which embody my invention; Fig. 1 being a plan view and Fig. 2 is an elevation. Figs. 3 and 4 show details of the construction, Fig. 3 being partly in section and Fig. 5 shows one method of its application.

In Figs. 1 and 2, 11 indicates the insulated base, 12 is the insulated conductors, 13 and 14 are the binding posts of the terminal; 15 is a nut to secure the wire on the binding post, 16 is a lock nut which also secures the metallic link 21 in place and thus provides for the continuity of the circuit. The link, in the present invention, is made 35 in two pieces, the metallic part 21 and the insulating piece, preferably of vulcanized fiber, 22; these two pieces are secured together by rivets 23, or other means which hold them in alignment.

40 The novelty in this arrangement consists, as shown in the enlarged details, Figs. 3 and 4, in providing in the metallic strip 21 an opening considerably larger than the diameter of the binding post 14 while the corresponding opening in the adjacent insulating 45 piece 22 is a comparatively close fit on the

binding post. The connecting link 21, has, preferably, a bias upward when clamped by the opposite post. It will thus be seen that when the nut 16 is unscrewed on the binding post 14, Fig. 3, the circuit is opened at 5 24 between the link 21 and the top of nut 15. The insulating piece 22 thus insulates the nut 16 from the connecting link 21 and at the same time prevents this link from 10 coming into contact with the binding post. When the nut 16 is tightened, the circuit is securely established between 15 and 21.

This idea, naturally, lends itself to a variety of applications and modifications without departing from the principle of the invention. For instance, on the middle terminal Fig. 1, the insulating piece 22 is shown as passing between both binding posts similar to the connecting link, while in the other 15 applications it is shown as passing only part way over the link. It should be noted that if the link is inverted, with the insulating piece on the under side and the bias removed from the link, it will still perform 20 the function of the present invention, the only difference in this case being that the link would make the circuit through the upper, instead of the lower nut.

In practice, limited space, makes it necessary 25 to place the terminals in rows close together. With the former type of link it was necessary to undo the nuts on both binding posts and remove the link from the terminal in order to open the circuit. Another type of link made in the form of a hook required releasing both lock nuts to 30 swing it open horizontally and was impractical when placed adjacent to other terminals due to the possibility of crossing with other circuits. The present invention controls the circuit by a comparatively small 35 vertical movement, which is quickly and easily effected. Only one nut has to be released and this nut clamps the fiber insulation which, from its nature, acts as a nut lock 40 to prevent the nut from turning.

One of the common uses to which this invention may be applied is illustrated in Fig. 5, this is in the application of a meter for 45 testing purposes. The battery B, operates the translating device 25 through the circuit

composed of wires 27, 28, 29 and 30. Between the wires 27-28, a terminal may be inserted as shown, and, where necessary, a corresponding terminal may be inserted between wires 29-30. The meter, or translating device 26, may be inserted in series in this circuit by "clipping" one lead 35 to the terminal 13 and another lead 36 to the terminal 14 and releasing the proper lock nut. Tests may be made between different terminals in a similar manner. Where desired, these terminals may be embodied as part of the testing instrument.

In certain classes of work, such as railway signaling, circuits are available for testing only at short intervals, this arrangement is well suited for conditions of this kind as the circuit can be instantly restored to normal conditions simply by the pressure of the finger on the link.

Combined with the features stated, this invention is also used as a means of designating the conductors of the circuit. The insulated piece 22 is such that it can be readily embossed by an embossing punch with the desired characters corresponding to the designation of the wires. This is shown in Fig. 1 where the top wire has a tag 31 with the designation "126 La HC 10", corresponding characters being placed on the insulating piece 22. Similarly the second wire is marked "Batt Pos." and the third wire "2232 JC 1", the piece 22 being correspondingly marked. If a wire becomes detached from its terminal its position can thus be readily found.

Having thus described my invention, I claim:

1. In combination, an electrical conductor, a plurality of binding posts, one of said binding posts having a plurality of nuts, a metallic connecting link secured to one of said binding posts and clamped between the nuts of the other binding post and forming part of said conductor, also, an insulated piece clamped between said nuts, said piece arranged to insulate said link from said post and one of said nuts.

2. In combination, an electrical conductor, a plurality of binding posts, one of said binding posts having a plurality of nuts, a metallic connecting link secured to one of said binding posts and clamped between the nuts of the other binding post and forming part of said conductor, also, an insulated piece clamped between said nuts, said piece insulating said link from said post and one of said nuts, and said link formed on a bias to follow said insulated nut when it is unscrewed.

3. In combination, an electrical conductor, a plurality of binding posts, one of said binding posts having a plurality of nuts, a

metallic connecting link secured to one of said binding posts and clamped between the nuts of the other binding post and forming part of said conductor, also, an insulated piece secured to said link and clamped between said nuts, an opening in said link larger than said binding post and an opening in said piece to fit said binding post closely.

4. In combination, an electrical conductor, a plurality of binding posts, one of said binding posts having a plurality of nuts, a metallic connecting link secured to one of said binding posts and clamped between the nuts of the other binding post and forming part of said conductor, also, an insulated piece secured to the upper side of said link and clamped between said nuts, an opening in said link and said piece for said binding post, the opening in said link being larger than the opening in said piece, said link having a spring action to follow the clamping nut engaging said piece when it is unscrewed.

5. In combination, an electrical conductor with a particular designation, a plurality of binding posts, one of said binding posts having a plurality of nuts, a metallic link secured to one of said binding posts and clamped between the nuts of the other binding post and forming part of said conductor, also, an insulated piece secured to said link and clamped between said nuts, said piece insulating said link from said post and one of said nuts, and said piece capable of being embossed with the designation of said conductor.

6. In combination, an electrical conductor, a plurality of binding posts, one of said binding posts having a plurality of nuts, a metallic connecting link secured to one of said binding posts and clamped between the nuts of the other binding post and forming part of said conductor, an insulated piece secured to said link and clamped between said nuts, and means for interrupting the continuity of said conductor by partially unscrewing one of said nuts.

7. In combination, an electrical conductor, a plurality of binding posts, one of said binding posts having a plurality of nuts, a metallic connecting link secured to one of said binding posts and clamped between the nuts of the other binding post and forming part of said conductor, an insulated piece secured to said link and clamped between said nuts, said link constructed with a bias, and means for interrupting the continuity of said conductor when said link follows said bias.

8. In combination, an electrical conductor, a plurality of binding posts, one of said binding posts having a lock nut, a metallic

link connecting said binding posts and forming part of said conductor, an insulated piece secured to said link and clamped by said lock nut, said piece preventing said lock 5 nut from turning.

Signed at Poughkeepsie, in the county of

Dutchess and State of New York, this 4th day of March, A. D. 1918.
